UNITED STATES PATENT OFFICE.

ALICE G. KILGORE, OF ST. PAUL, MINNESOTA.

DESIGN FOR A PACKAGE CONTAINING CANDY.

59,601.

Specification for Design.

Patented Nov. 8, 1921.

Application filed February 23, 1921. Serial No. 447,337. Term of patent 14 years.

To all whom it may concern:

Be it known that I, ALICE G. KILGORE, a citizen of the United States, residing at St. Paul, in the county of Ramsey and State of Minnesota, have invented a new, original, and ornamental Design for a Package Containing Candy, of which the following is a specification, reference being had to the accompanying drawing, forming part thereof.

Figure 1 is a front elevation, and
Fig. 2 is an edge view showing my design.

I claim:

The ornamental design for a package containing candy, as shown.

ALICE G. KILGORE.
